(57) **CLAIM**

The ornamental design for a controller for computer, as shown and described.

DESCRIPTION

FIG. 1 is a front side perspective view of a first embodiment of a controller for computer showing our new design;
FIG. 2 is a back side perspective view thereof;
FIG. 3 is a front view thereof;
FIG. 4 is a back view thereof;
FIG. 5 is a top view thereof;
FIG. 6 is a bottom view thereof;
FIG. 7 is a right view thereof;
FIG. 8 is a left view thereof;
FIG. 9 is a front view of a second embodiment of a controller for computer showing our new design;
FIG. 10 is a back view thereof;
FIG. 11 is a top view thereof;
FIG. 12 is a bottom view thereof;
FIG. 13 is a right view thereof; and,
FIG. 14 is a left view thereof.

1 Claim, 14 Drawing Sheets
